US00D886077S

(12) **United States Design Patent** (10) **Patent No.:** **US D886,077 S**
Chen et al. (45) **Date of Patent:** **** Jun. 2, 2020**

(54) **POWER SUPPLY OF A BONE CONDUCTION HEADSET**

(71) Applicant: **SHENZHEN VOXTECH CO., LTD.**,
Shenzhen, Guangdong (CN)

(72) Inventors: **Hao Chen**, Guangdong (CN); **Fen You**,
Guangdong (CN); **Yueqiang Wang**,
Guangdong (CN)

(73) Assignee: **SHENZHEN VOXTECH CO., LTD.**,
Shenzhen (CN)

(**) Term: **15 Years**

(21) Appl. No.: **29/653,144**

(22) Filed: **Jun. 12, 2018**

Related U.S. Application Data

(62) Division of application No. 29/585,454, filed on Nov.
23, 2016, now Pat. No. Des. 823,279.

(30) **Foreign Application Priority Data**

Apr. 21, 2016 (CN) 2016 3 0137222

(51) **LOC (12) Cl.** **14-01**

(52) **U.S. Cl.**

USPC **D14/205**

(58) **Field of Classification Search**

(57) CLAIM

The ornamental design for power supply of a bone conduction headset, as shown and described.

DESCRIPTION

FIG. 1 is a perspective view of a power supply of a bone conduction headset showing our new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

1 Claim, 6 Drawing Sheets
